UNITED STATES PATENT OFFICE.

ALFRED COTTON, OF NEWARK, NEW JERSEY.

AIR-REGULATOR FOR FURNACES.

No. 899,102.

Specification of Letters Patent.

Patented Sept. 22, 1908.

Application filed November 4, 1907. Serial No. 400,479.

To all whom it may concern:

Be it known that I, ALFRED COTTON, a subject of the King of Great Britain, residing at Newark, in the county of Essex and State 5 of New Jersey, have invented certain new and useful Improvements in Air-Regulators for Furnaces, of which the following is a specification, reference being had therein to the accompanying drawings, in which—

10 Figure 1 is a front elevation of a furnace provided with my invention, a portion of the furnace being broken away to show the steam reservoir within the furnace; Fig. 2 a detail view of the fire door showing the valve and 15 nozzle for supplying air to the door; Fig. 2^a a diagrammatic view of the pipes and valves shown in Fig. 1, illustrating the relative positions of the controlling valves; Fig. 3 a front elevation of a furnace showing a 20 slightly different arrangement of the apparatus, a portion of the furnace being broken away to show the steam reservoir therein; and Fig. 4 a front elevation showing another arrangement of the invention.

25 This invention relates to apparatus for controlling the admission of air to furnaces for burning the gases arising from the primary combustion on the grates. It is adapted for use with all kinds of solid fuel, but 30 more particularly with bituminous coal and other smoky fuels, to reduce or do away with the emission of smoke.

The object of my invention is to provide an apparatus which will supply a large 35 amount of air over the fire for a predetermined time, said charge of air gradually diminishing to the minimum supply or entirely ceasing at the end of the fixed interval, this 40 interval of time being governed by the length of time the fire door is open during the charging operation.

Another object of the invention is to provide an apparatus which will automatically govern the amount of air supplied to the fire 45 box after each charging of fuel, the fireman or stoker being thus relieved of all responsibility as to the amount of air thus supplied.

Referring to the various parts by numerals, 1 designates the boiler, 2 the main steam 50 pipe which conveys steam to the main ash pit blower 3. The fire door 4 is provided with a vertical blower 5 similar to the blower shown in my pending application for patent Serial No. 307,982, filed March 26, 1906 55 through which air may be supplied over the

grate, as described in my said application. A steam reservoir 6 is connected at one end to the main steam pipe by a pipe 7. The other end of this reservoir is connected by a pipe 8 to the jet nozzle 9. As arranged in 60 the drawing this nozzle 9 is adapted to deliver air into the upper open end of the blower 5. It is obvious that the pipe 8 may be extended to any point where it may be desired to deliver the air, it being arranged 65 as shown in the drawings merely for convenience.

In the pipe 7 is arranged a valve 10, on the stem of which is secured a weighted lever 11 normally holding the valve open. One end 70 of this lever is connected by a chain 12 to the fire door in such manner that when said door is closed the valve will be moved to its closed position, and when said door is open the valve will be opened by the weighted lever. 75 It will thus be seen when the fire door is closed communication between the reservoir 6 and the pipe 2 will be closed.

In the pipe 8 is arranged a valve 13 whose valve stem 14 is adapted to be engaged by an 80 arm 15 carried by the fire door. On this arm is arranged an adjustable contact pin 16 which may be adjusted to contact with the valve stem 14 at the proper position of the fire door to operate said valve. The valve 13 85 is of the ordinary self-closing type shown in my application hereinbefore referred to, and said valve is arranged to be opened by the fire door arm when the fire door is closed, said valve automatically closing when the 90 fire door is open. As shown in Fig. 1 the steam reservoir 6 is arranged within the furnace flue and receives heat from the furnace so that it will serve as a steam superheater.

In operation the opening of the fire door to 95 charge the furnace with fuel will open the valve 10 and permit steam to pass into the reservoir 6 at boiler pressure, the valve 13 being closed. Upon the closing of the fire door, valve 10 will be closed shutting off 100 communication between the reservoir 6 and the pipe 2 and the valve 13 will be opened through the arm 15, thereby permitting the steam confined in the reservoir 6 to escape by way of the nozzle 9 into the blower 5, and 105 from said blower it may pass into the fire box as described in my said application. It will, of course, be understood that the nozzle 9 may be placed at any suitable point and the air thus supplied wherever it may be desired. 110

It is obvious that when the fire door is first closed steam will rush from the nozzle 9 under a great pressure and a large amount of air will be thus supplied to the fire, and this amount will gradually decrease as the pressure in the reservoir 6 decreases until finally the jet ceases operating.

It will be seen that the supply of air as controlled by my apparatus is large at first when the hydrocarbons are being given off in the greatest quantity immediately after charging fresh coal; and that the supply of air diminishes as the quantity of hydrocarbons decreases, until the only supply of air is that which is drawn through the fire door blower by the natural or chimney draft.

In some cases, such as where the furnaces are operated with slight pressure in the furnace-chamber it is evident that the jet of steam from the nozzle 9 must never be entirely interrupted while the fire door is closed, or rather, while the main blast is on. (In cases where pressure is maintained in the furnace-chamber it is necessary to interrupt the main air supply before opening the fire door, thus allowing some vacuum in the furnace chamber.) In such cases I provide either an adjustable by-pass 17 around the valve 10, or arrange that the valve 10 is prevented from completely closing by an adjustable stop. This insures that the pressure in the reservoir 6 will never quite fall to zero.

A somewhat similar result may be attained by disconnecting the chain 12 from the fire door so that the valve 10 will remain permanently open, and then setting the valve 18 slightly open or sufficient to give the necessary minimum pressure at the nozzle 9. When the fire door is open, permitting the valve 13 to close, pressure accumulates in the reservoir so that when the fire door is closed and the valve 13 opened the accumulated pressure in the reservoir 6 will be delivered through the nozzle 9 into the blower 5, thereby delivering a greater amount of air over the fire for a time, as in the other cases described, the supply of air gradually diminishing until the normal minimum pressure is reached.

The size of the reservoir 6 is proportioned according to the quality and consumption of coal. Adjustments of the capacity of an existing reservoir may be made by introducing or removing articles such as glazed bricks or hollow steam-tight globes or cylinders through the door 19 which is adapted to be closed steam-tightly. The size of the nozzle 9 may be varied, or the rate of flow of steam to it varied by a valve 20, in pipe 8 to suit circumstances.

The steam pipe 7 is described as being connected to the steam pipe supplying the main blower. In some cases, such as where there is no forced-draft, this pipe is carried either

directly from the boiler, or from some point where full or sufficient pressure may be obtained.

The reservoir 6 may be placed in any convenient position, but should be so placed that any water of condensation will naturally drain away through the pipe 8.

The apparatus is described as controlling the supply of air admitted through a fire door, but it may be used to control the supply of air admitted in any other manner instead of, or in addition to, the fire door supply. It may be applied to control the air supply to any type of furnace whether for steam-generation or otherwise; and if steam is not available it may be operated by compressed air.

A valve 18 is shown in pipe 7 between valve 10 and the pipe 2. This valve may be used to interrupt the operation of the apparatus for repairs or any other reason. It may also be used for adjustment of the supply of air as follows. If it is only slightly open, it is obvious that the pressure in the reservoir 6 will not reach that of the boiler during the usual time the fire door and consequently the valve 10 is open. If the fire door is kept open for a longer period due to charging an unusually large amount of coal, the pressure in the reservoir 6 will rise higher—perhaps as high as boiler pressure—and a greater quantity of air will be delivered in unit time in accordance with the extra supply of coal, and the supply of air will be longer continued—again in accordance with the longer time required to distil off the hydrocarbons from the extra coal.

It is manifest that valve 13 may be dispensed with and the normal discharge of steam through the nozzle 9 controlled by valve 20. In this arrangement, upon opening the fire door and consequently opening the valve 10, steam is admitted to the reservoir faster than it can escape from the nozzle and the pressure on the reservoir rises. On closing the fire door and consequently closing the valve 10, the pressure in the reservoir gradually falls, thereby diminishing the supply of air. It will, therefore, be seen that I desire to accumulate in the reservoir 6 a surplus fluid pressure which may be discharged into the furnace when the fire door is closed, said supply gradually diminishing to zero or to a minimum normal supply.

As shown in Fig. 3 the steam reservoir 6* is located in the furnace wall or in any desired position to receive heat from the furnace so as to serve as a superheater. The reservoir is connected to the boiler by pipe 22 controlled by valve 23. From the reservoir 6* a pipe 24 leads to a blower 25. In this pipe 24 is a valve 26 by means of which the supply of steam to the blower may be entirely stopped. A valve 27 similar to valve 13 is also provided in this pipe, said

valve being opened by the arm 28 on the fire door, and automatically closing when the fire door is open. By this arrangement of the apparatus steam will accumulate in the reservoir 6^a when the fire door is open and when the said door is closed the accumulated steam will be discharged into the blower 25. The valve 23 controls the normal discharge of steam through the blower 25, and it is manifest that when the valve 27 is closed steam will be accumulated in the reservoir 6^a and that the accumulated steam will be rapidly discharged into the blower 25 upon the closing of the fire door until the flow of steam through pipe 24 has been reduced to normal.

As shown in Fig. 4 the charging of the reservoir 6^b with steam is controlled by the opening of the fire door. In this arrangement valve 10 is connected by a weighted lever 11^a and chain 12^a to the fire door so that when the said door is opened valve 10^a is opened and reservoir 6^b charged with steam. In this arrangement the steam reservoir is connected by a pipe 8^a to a pair of blowers 28 and a valve 29, the pipe 8^a controls the supply of steam to said blowers. The operation of this arrangement of my invention is quite obvious. The valve 29 controls the normal supply of steam to the blowers 28. When the fire door is open valve 10^a is open and steam from the boiler flows into the reservoir 6^b and to the blowers. The valve 29 is set so that it has a smaller outlet than the valve 10^a. The result of this is that steam will flow into the blowers when the fire door is open and will also accumulate in the reservoir 6^a, this surplus accumulation flowing into the furnace 40 through the blowers after the fire door and valve 10^a are closed. In this arrangement of the apparatus there is a discharge of steam into the furnace when the fire door is opened, the discharge valve operated by the fire door, shown in Figs. 1 and 3, being dispensed with.

Having thus described my invention, what I claim as new and desire to secure by Letters Patent, is:—

- 50 1. An air regulator for a furnace comprising a reservoir, means for supplying steam to said reservoir, a pipe leading the steam from said reservoir to the fire in the furnace, in combination with a fire door and means operated by said door in opening and closing to permit steam to flow to said reservoir when the fire door is open, and to stop the flow of steam to said reservoir when the fire door is closed.
- 60 2. An air regulator for a furnace comprising a reservoir, a pipe connecting said reservoir to a steam supply, a pipe leading steam from said reservoir to the fire in the furnace, in combination with a fire door and means operated thereby in opening and closing to

permit steam to flow from said reservoir to the fire when the door is closed and to prevent steam flowing from said reservoir when the door is open.

3. An air regulator for a furnace comprising a reservoir, means for supplying fluid under pressure to said reservoir, means for permitting the fluid to flow from said reservoir to the fire in the furnace in combination with a fire door, and means controlled by the movement of the fire door to charge the reservoir when the door is open and to permit the escape of fluid from said reservoir when the door is closed. 70

4. An air regulator for a furnace comprising a reservoir, means for supplying fluid under pressure to said reservoir, a valve controlling said supply, a pipe connected to said reservoir and arranged to deliver fluid therefrom to the fire in the furnace, a valve in said pipe controlling the movement of fluid from said reservoir in combination with a fire door, and means whereby the opening and closing of said door will operate said valves to first charge the reservoir when the door is open and to permit the fluid from said reservoir to flow to the fire in the furnace when the fire door is closed. 80

5. An air regulator for a furnace comprising a reservoir, a pipe for supplying fluid under pressure to said reservoir, a pipe to permit the escape of fluid from said reservoir and arranged to deliver said fluid to the fire in the furnace, an inlet valve in the supply pipe, an outlet valve in the escape pipe in combination with a fire door and means connected thereto and adapted to alternately operate the inlet valve and the outlet valve, whereby the reservoir will be charged when the fire door is open and the fluid will be permitted to escape therefrom and be delivered to the fire when the fire door is closed. 90

6. An air regulator for a furnace comprising a reservoir, a pipe for supplying fluid under pressure to said reservoir, a pipe to permit the escape of fluid from said reservoir and arranged to deliver said fluid to the fire in the furnace, an inlet valve in the supply pipe, an outlet valve in the escape pipe in combination with a fire door and means operated thereby to open the inlet valve and close the escape valve when the fire door is open and to close the inlet valve and open the escape when the fire door is closed. 100

7. An air regulator for a furnace comprising a reservoir, means for supplying fluid under pressure to said reservoir, means for permitting the fluid to flow from said reservoir to the furnace fire, means to restrict the flow of fluid to said reservoir in combination with a fire door, and means controlled by the movement thereof to permit the escape of fluid from said reservoir when the door is closed. 110

8. An air regulator for a furnace comprising

ing a reservoir arranged to be heated in the furnace and serving as a superheater, means for supplying steam to said reservoir, a blower arranged to deliver air and steam to the fire, means connecting said reservoir to the blower in combination with a fire door and means operated by the fire door to permit steam to be discharged from the reservoir into the fire when the fire door is closed and 10 to prevent the discharge of steam when the fire door is open.

9. The combination of a furnace, a reservoir, means for supplying steam to said reservoir, means for permitting the steam to flow

from said reservoir to the fire in the furnace, 15 a fire door and means controlled by the movement of the fire door to charge the reservoir when the door is open and to permit the escape of steam from said reservoir when the door is closed.

In testimony whereof I hereunto affix my signature in the presence of two witnesses this 31st day of October 1907.
